ROY M. OTARI AND THOMAS R. SCHOENLEBER, OF SEATTLE, WASHINGTON.

FEEDING MECHANISM.

1,262,383.

Specification of Letters Patent. Patented Apr. 9, 1918.

Application filed December 4, 1916. Serial No. 135,084.

To all whom it may concern:

Be it known that we, ROY M. OTARI, a subject of the Emperor of Japan, and THOMAS R. SCHOENLEBER, a citizen of the United States, residing at Seattle, in the county of King and State of Washington, have invented a certain new and useful Improvement in Feeding Mechanism, of which the following is a specification.

10 Our invention relates to improvements in feeding mechanisms of machines which are employed to operate on pieces of sheet material, as printing presses, machines for making paper boxes, machines for making sheet metal boxes, and the like, and the object of our invention is to provide mechanism which may be embodied in or associated with, any of said machines, in such manner that it shall be adapted to 15 operate on a pile of pieces of sheet material reliably to transfer said pieces from said pile, only one at a time, to the position where said pieces are successively to be operated upon by the associated machine.

20 We accomplish this object by devices which are illustrated in the accompanying drawings as embodied in a machine which is especially adapted to print a desired form of indorsement upon the back of each of 25 successive ones of a pile of bank checks, and in which drawings Figure 1 is a plan view of a machine embodying my invention; Fig. 2 is a view of the same in side elevation; Fig. 3 is a view of the same in rearward 30 end elevation, but showing certain parts in vertical section; and Fig. 4 is a view of the same in vertical section on broken line 4, 4 of Fig. 1.

35 Referring to the drawing, throughout 40 which like reference numerals indicate like parts, a frame is formed of four vertical corner studs 5, 6, 7 and 8 of which the studs 5 and 6 are disposed opposite each other at the rearward end of the frame while the 45 studs 7 and 8 are opposite each other at the frontward end thereof, the studs 5 and 6 being of greater height than are the studs 7 and 8, and all of said studs being rigidly connected by lower transverse bars 9 and 50 10, upper transverse bars 11 and 12, lower longitudinal bars 13 and 14, and upper longitudinal bars 15 and 16.

Rotatably mounted in suitable bearings formed one in each of the vertical studs 5 and

6 at opposite points therein, is a shaft 17 one 55 end portion of which projects outwardly from the outer side of said stud 6, and upon such outwardly projecting portion is rigidly mounted a fly wheel 18 provided with a 60 crank 19 which may be manipulated to rotate said shaft 17.

Rotatably mounted in bearings, formed one in each of the shorter studs 7 and 8 at opposite points therein, with its axis in the same horizontal plane with the axis of the 65 shaft 17, is a shaft 20, and upon each of the shafts 17 and 20 is concentrically fastened a cylinder, as cylinders 21 and 22, respectively, that extends substantially throughout the distance between the studs 5 and 6 70 and between the studs 7 and 8 respectively.

A conveying belt 23, of suitable material, is operatively mounted on said cylinders 21 and 22 to extend therebetween and to travel in response to revolutions of the shaft 17, 75 thus to serve as a conveyer, said belt 23 being of a width that is nearly equal to the length of said cylinders 17 and 18.

Secured to the upper edge portions of the longitudinal bars 15 and 16 to extend there- 80 between adjacent to the studs 7 and 8, is a cross-bar 24 whose top surface engages with the inner side of the conveying belt 23, thus to prevent a deflection of said belt 23 in response to a pressure exerted on its outer 85 upper side as it travels between the cylinder 21 and the cylinder 22.

A box-like receptacle 25 is secured to the studs 7 and 8, and disposed to extend therebetween, its front end portion extending for 90 a distance from said studs 7 and 8 of the forward end of the frame, said receptacle 25 being provided with a bottom wall 26, as shown in Fig. 4, which bottom wall 26 serves as the floor of said receptacle 25, and 95 which extends from the vertical front end of said receptacle 25 to a line spaced from the forward sides of the studs 7 and 8, thus to form an opening 27 between the rearward edge of said bottom wall 26 and the surface 100 of the belt 23, said receptacle 25 having no vertical rearward wall adjacent to the studs 7 and 8.

The top surface of the bottom wall 26, which serves as a floor of the receptacle 25 is 105 in the same horizontal plane with the surface of the upper outer side of the belt 23.

Extending between the studs 5 and 7 on

one side of the frame and between the studs 6 and 8 on the other side thereof are side guides 28 and 29, respectively, whose bottom edges are in the same horizontal plane with the top surface of the bottom wall 26 of the receptacle 25.

The opposite inner sides of the upper portion of the studs 7 and 8 are provided with parallel vertical grooves 30 and 31, 10 which grooves 30 and 31 extend downwardly from the tops of the studs 7 and 8 to a line near the plane of the top surface of the belt 23.

Disposed to be vertically slidable within the opposite slots 31 is a transverse bar 32 whose lower edge portion is curved from its front side downwardly and rearwardly to its rearward side, and to its rearward side edge portion is fastened a strip 33 of suitable soft yielding material of a length equal to the width of the belt 23, the yielding material of which strip 33 may consist of soft felt, a strip of plush textile fabric filled with a padding of cotton or wool, or it may consist of a soft brush, the underside of said strip 33 being disposed to project downwardly lower than the bottom edge of the slidably transverse bar 32 to which it is fastened whereby its bottom edge may yielding engage with the outer upper surface of said belt 23.

The force of the yielding engagement of said strip 33 is adjustably regulated by the rotation of adjusting screws 34 provided in the transverse bar 12, the points of which adjusting screws 34 are associated with helical compression springs (like the spring 35) disposed on the top surface of the vertically slidable transverse bar 32.

Disposed to be slidably vertical within the opposite disposed slots 30 of the studs 7 and 8, to extend therebetween, is another transverse bar 36, as shown in Fig. 4, to the bottom edge of which transverse bar 36 is attached a brush 37, which extends for a distance equal to the width of the belt 23, the bristles of which brush 37 are disposed yielding to engage with the surface of the upper portion of said belt 23.

The force of the yielding engagement of the bristles of the brush 37 with the belt 23 may be adjustably regulated, by adjusting screws 38 and associated helical springs like the helical spring 39 shown in Fig. 4, 55 in a manner similar to that by which the yielding engagement between the strip 33 and the belt 23 is regulated.

Rotatably disposed in bearings formed at opposite points in the studs 5 and 6 beneath the cylinder 21 is a shaft 40 upon which is concentrically mounted a cylinder 41 which is covered with a layer 42 of suitable soft, elastic, compressible material, as, for instance, the gelatin-like composition of 65 which printer's ink rollers are made, soft

blotting paper, or felt, which layer is disposed yieldingly to engage with the outside surface of the lower portion of the moving belt 23 at the point where said belt 23 leaves the periphery of the cylinder 17, as shown in Fig. 4.

Both of the vertical studs 5 and 6, from their top ends downwardly to points near the bearings of the shaft 17, are bifurcated by slots like the slot 43, and upon the bottom of each of said slots is disposed a cushion 44 of yielding material, as soft vulcanized rubber, and within the slot 43 of each of the studs 5 and 6 is a shaft bearing block, like the shaft bearing block 45 shown in Fig. 3, 80 which bearing block 45 is yieldingly supported by a cushion 44.

Upon the top of each of the bearing blocks 45 is removably disposed a shive, like the shive 46 shown in Fig. 3, which shive 46 may be of unyielding material, or of material less yielding than is the material of the cushion 44.

Upon the top of the shives 46, within the slots 43, are oppositely disposed shaft- 90 bearing blocks 47.

Upon the top of each of the bearing blocks 47 is disposed a helical compression spring 48 whose top end is associated with an adjusting screw, as adjusting screws 49, 95 which extends through the transverse bar 11, whereby a rotation of said adjusting screws 49 may cause the helical springs 48 to exert a greater or lesser force which tends to force downwardly the bearing blocks 47 100 and 45 in opposition to the action of the cushion 44.

Rotatably mounted within the bearings of the bearing blocks 45 is a shaft 50, one end portion of which projects outwardly from the outer side of the stud 5, and mounted in the bearings of the bearing blocks 47 is a shaft 51, one end portion of which also projects outwardly from the outer side of said stud 5.

Fixed on the outwardly projecting end portions of both of the shafts 50 and 51 are gearwheels 52 and 53, respectively, which operatively engage with each other, said gearwheel 52 also being adapted to engage with another gearwheel 54 which is fixed on the adjacent end of the shaft 17 whereby a rotation of the shaft 17 will cause the shafts 50 and 51 to rotate synchronously therewith.

Concentrically mounted upon the shaft 50 is a cylinder 55 upon opposite portions of which are fixed type-holding devices 56 and 57 which are adapted to hold removable type, or removable stereotypic plates in such positions that the bases of their type will be in a circle concentric with the axis of the shaft 50; such circle being of a diameter to cause the faces of such type to engage with the outside surface of the belt 23 as said

belt 23 is caused to pass around the periphery of the cylinder 21 in response to a rotation of the shaft 17.

Concentrically mounted on the shaft 51 5 is a cylinder 58 upon which is concentrically mounted an ink surface 59, of well known material, which ink surface is disposed to engage with the faces of the type or stereotype carried by the cylinder 55.

10 Thus, if a piece of paper be laid upon the belt 23 and thereupon the shaft 17 be rotated by the crank 19, in the direction of the arrow shown in Fig. 4, then said belt 23 will carry said piece of paper between the cylinder 21 and the face of the type mounted on the cylinder 55, thus to cause such type to print their characters on said piece of paper, and as said piece of paper passes outwardly from between the cylinders 51 and 55 15 it passes on to a transversely disposed plate 60 whose ends are fastened to the studs 5 and 6 to extend therebetween, as indicated in Fig. 4.

Secured to the frontward sides of the vertical studs 7 and 8, adjacent to the opening 27, are oppositely disposed bearing brackets 61 and 62, within which is rotatably mounted a shaft 63 that is provided with oppositely disposed yielding fins 64, of flexible sheet material, which extends lengthwise of said shaft 63 for a distance equal to the width of the interior of the receptacle 25, and said shaft 63 is so disposed that the edge portions of said fins 64 project above 30 the plane of the floor of the receptacle 25 as they are revolved by the shaft 63.

One end portion of the shaft 63 projects outwardly beyond the vertical plane of the outer side of the stud 7, and on said outwardly projecting end portion is a grooved pulley 65 whose groove registers with the groove of another grooved pulley 66 which is fastened on to the adjacent outwardly projecting end portion of the shaft 20 that 40 is adapted to be rotated by the belt 23 in response to a rotation of the driving shaft 17.

Operatively mounted on the grooved pulleys 65 and 66 is a belt 67, of circular cross-section, by which motion may be communicated from the shaft 20 to the shaft 63.

The machine which thus embodies our invention as illustrated and described is especially adapted for use in banks and in 55 clearing houses of associated banks for the purpose of indorsing a large number of bank checks and bank drafts much more quickly than such papers can be handled and indorsed by a hand stamp, and its operation may be described as follows:

A pile of bank checks as bank checks designated by the numerals 68 in Figs. 1 and 4, are disposed within the receptacle 25 all with their backs upward to rest upon 65 the bottom wall 26 of said receptacle 25.

Thereupon the crank handle 19 is manipulated to actuate the belt 23 to travel in the direction of the arrow shown in Fig. 4, with the result that rotary motion will be communicated to the shaft 63 thereby to 70 cause the flexible fins 64 frictionally to engage with the lowermost one of said bank checks 68 with the result that said lowermost bank check will be bulged upwardly and carried forward to cause its edge portion to be deflected downwardly from the adjacent one of the other bank checks, then such edge portion is engaged by the frictional surface of the belt 23 to which it is pressed by the strip 33 whereby said belt 80 23 will carry said lowermost one of said bank checks 68 rearwardly to pass between the cylinder 21 and the rotating face of the type associated with the cylinder 55 thus to print upon the back of said bank 85 check the characters of said type which may constitute the required indorsement.

The adjacent one of the upper bank checks will be detained by the strip 33 and the brush 37 until after the preceding bank 90 check has left the brush 37. Thus successive ones, and one at a time only, of said pile of bank checks 68 will be indorsed in response to revolutions of the shaft 17 irrespective of rate of speed at which said shaft 95 17 may be driven.

The adjusting screws 34 and 38 may be actuated to adjust accurately the required pressure on the successive bank checks 68 and the adjusting screws 49 may serve to 100 cause the compression springs 48 to exert a required pressure on the cylinder 55, the shives 46 being made of a thickness that will cause the ink roller 59 properly to ink the type associated with the cylinder 55. 105

The layer 42 of material on the cylinder 41 by its contact with the outer side of the belt 23 serves to act like a blotter to absorb and remove any ink that may accidentally or incidentally be deposited thereon thus to keep the face of bank checks free 110 from blots.

Obviously, feeding mechanism embodying our invention may be embodied in any machine which is designed to operate upon successive pieces of sheet material, and, manifestly, changes may be made in the forms, dimensions and arrangement of parts of our invention without departing from the spirit thereof. 115

What we claim is:

1. A feeding mechanism of the class described, which embodies a supporting frame; two shafts rotatably mounted in bearings fixed in said frame, said shafts being disposed parallel with and spaced from each other; a cylinder concentrically mounted on each of said two shafts, one of said cylinders constituting the receiving end portion of a conveyer and the other constituting the de- 125 180

- livery end portion of said conveyer; an endless conveyer belt operatively mounted on said two shafts and adapted to receive successive pieces of sheet material at the uppermost portion of the periphery of the cylinder at the receiving end portion of said conveyer and successively to carry said pieces and deliver them from the uppermost portion of the periphery of the cylinder of the delivery end portion of said conveyer; a support disposed with one of its edges parallel with and spaced from the cylinder at the receiving end of said conveyer with its top surface substantially in the same plane with the uppermost surface of said conveyer belt and adapted to support a pile of pieces of sheet material in such position that an edge of the lowermost one of said pieces shall be adjacent to the uppermost surface of said conveyer belt; a strip of soft yielding material adjustably disposed to engage with the uppermost surface of said belt conveyer on a transverse line thereof that is adjacent to the uppermost portion of the periphery of the cylinder at the receiving end of said conveyer; a brush adjustably disposed to engage its bristles with the uppermost surface of said belt conveyer through a transverse line thereon adjacent to the rearward side of said strip of soft yielding material; a shaft rotatably disposed between that cylinder at the receiving end of the conveyer and the adjacent edge of said support in parallel line therewith, and provided with oppositely disposed flexible fins that project radially from its cylindrical surface for such distance as will cause their edges to intersect the plane of the top surface of said support in response to a rotation of said shaft whereby the bottom one of a pile of pieces of sheet material will be engaged by said fins to move such one piece into engagement with said belt conveyer and said strip of soft yielding material thus to cause said piece to be withdrawn from said support by the joint action of said belt conveyer and
- said strip of soft yielding material; and means for communicating rotary motion from said shaft of that cylinder at the receiving end of the conveyer to that shaft 50 provided with said fins.
2. A feeding device of the class described comprising a pair of spaced rollers, a belt connection between said rollers, rotatable means engaging said belt adjacent one of 55 said rollers, a support adapted to contain a plurality of superposed sheets of material, means operated by the movement of said belt singly to feed the sheets to said belt, and tensioned means positioned above said belt to engage the same to insure the single feeding of said sheets.
3. A feeding device of the class described comprising a pair of spaced rollers, a belt connection between said rollers, a support 65 adapted to contain a plurality of superposed sheets of material and means operated by the movement of said belt singly to feed the sheets to said belt, and a regulable tensioned brush element arranged above the belt to 70 engage the same to insure single feeding of the sheets.
4. A feeding device of the class described comprising a pair of spaced rollers, a belt connection between said rollers, rotatable 75 means engaging said belt adjacent one of said rollers, a support adapted to contain a plurality of superposed sheets of material and means operated by the movement of said belt singly to feed the sheets to said 80 belt, and a tensioned abutment and tensioned flexible member arranged adjacent the pile of sheets and said belt to insure the single feed of the sheets.

In witness whereof, we hereunto subscribe 85 our names this 22nd day of November, A. D., 1916.

ROY M. OTARI.

THOMAS R. SCHOENLEBER.
